ELEVATING MECHANISM FOR MACHINE
TOOL KNEES

Frank W. Curtis, Springfield, Mass., assignor to
Van Norman Company, a corporation of Massa-
chusetts

Original application March 8, 1940, Serial No.
322,973, now Patent No. 2,301,525, dated No-
vember 10, 1942. Divided and this application
November 27, 1940, Serial No. 367,326

1 Claim. (Cl. 90--53)

This invention relates to improvements in elevating mechanism for the knees of machine tools, and is a division of my application Serial No. 322,973, filed March 8, 1940, now Patent No. 2,301,525, granted November 10, 1942.

One object of the invention is to improve the knee structure so as to give improved stability and guidance to the elevating mechanism and so that the elevating mechanism itself will contribute to the stability of the knee. A further object is to improve the drive and stability of operation of the knee to the end that smooth operation and freedom from chatter will be present even when the elevating mechanism is driven at a rapid traverse rate. A further object is to provide a construction of knee elevating mechanism in which the telescopic parts extending between the vertically movable knee and base will have a maximum protection against dirt and metal chips. A further object is to provide a construction which will prevent leakage of oil from the interior of the knee when, as is preferable, the knee acts as an oil reservoir for the gearing contained in it. Additional objects will appear from the following description and claim.

Referring to the drawings.

Fig. 1 is a side elevation, partly broken away, of a machine tool knee embodying the present invention;

Fig. 2 is a sectional plan through the knee structure;

Fig. 3 is a detail of the knee elevating screw;

Fig. 4 is an enlarged detail of a portion of Fig. 1; and

Fig. 5 is a diagrammatic view of the gearing for operating the knee elevating mechanism at either feed or rapid traverse rate.

The machine is shown as mounted on a base A, a column B arising from the base and having ways upon which the knee C slides vertically. Additional parts, such as a saddle and a table, are generally used in connection with the knee, and have been described in the parent application referred to. Parts other than those concerned in giving the knee its vertical movement have been omitted from the present disclosure.

The power feed for the knee is derived from a vertical shaft 29 mounted in the base A and extending vertically into telescoping relation with the knee. This shaft may be driven from a suitable motor in a way not necessary to show here. The shaft 29 is splined as is shown in Figs. 2 and 4 and passes through the downwardly projecting shank 21 of a bevel gear 22 held in the knee structure by anti-friction bearings 23. In order

to keep oil from leaking down the splines on this shaft a sleeve 24 is fitted into the bevel gear 22 and extends upwardly nearly to the top of the knee, being provided with a cap 25. In Fig. 1 the knee is shown in its lowermost position, and as the knee rises, the shank 21 and the sleeve 24 will slide upwardly on the splined shaft.

Meshing with the gearing 22 is a second bevel gear 28, the shank 27 of which is mounted in anti-friction bearings 26 carried by the knee structure. The shank 27 carries one member 29 of a rapid traverse friction clutch, here shown as being of a standard multiple plate type. The driven clutch member 30 is carried by a sleeve 31 reciprocable upon a common drive shaft 32 which is splined at its end adjacent the sleeve so that while the sleeve may reciprocate upon the shaft it is always coupled in driving relation to it. As will be seen from Fig. 1 the shaft 32 has a bearing portion 33 within the shank 27 of the gear 26.

The knee elevating mechanism is driven from the common drive shaft 32; and this shaft, as well as being driven directly from the gear 26 through the rapid traverse clutch, may also be driven through the gearing now to be described at any of eighteen feed rates. For this purpose a gear 35 (see Fig. 2) is secured to the face of the bevel gear 28 and meshes with a gear 36 rotatably mounted in the knee structure. Fixed to the gear 36 is a pinion 37 meshing with a gear 38. Positively coupled to this latter gear is a second pinion 39 meshing with a gear 40 coaxial with the gear 36. A splined shaft 41 (Fig. 5) passes freely through the gear 40 and has coupled to it a clutch member 42 shiftable alternatively into engagement with cooperating complementary clutch members formed on gear 36 and gear 40. In this way the splined shaft 41 may be driven either directly from the constantly rotating gear 36 or through the gear train 37, 38, 39, 40 which acts similarly to back gears to produce a lower rate of rotation of the driven shaft.

The splined shaft 41 carries a gear 43 meshing with a larger gear 44 upon a shaft 45 (Figs. 2 and 5) journaled in the knee and provided at its end remote from the gear 44 with a splined portion upon which a cluster gear 46 slides. This gear is composed of three gears 47, 48, and 49 which mesh respectively with gears 50, 51, and 52 upon a parallel idler shaft 53. A second cluster gear 54 is mounted for reciprocation on a splined sleeve 55 journaled for free rotation about the common drive shaft 32 previously de-

scribed. This second cluster gear comprises gears 56, 57, and 58 meshing respectively with gears 59, 51, and 60 on the intermediate shaft 53. By shifting the cluster gear 46 three changes of feed rate may be secured. Each of these can be varied in three ways by shifting the cluster gear 54, making a total of nine changes of feed rate for sleeve 55, and each of these nine feed rates may be varied from a high rate to a low rate by means of the clutch 42, making a total of eighteen possible feed rates.

The splined sleeve 55, see Figs. 1, 2 and 5, carries a clutch member 61 cooperating with a clutch member 62 on the sleeve 31 previously referred to as being keyed on the drive shaft 32. This drive shaft extends to the front of the knee and has fixed to it a gear 67 which may, as set forth in the parent application, be formed as an overload release. Gear 67 meshes with a wide-faced gear 75. A gear 77 upon a reversing shaft 78 meshes with gear 75, the shaft 78 also having a gear 79 fixed to it. The knee drive shaft 80 has gears 81 and 82 mounted to revolve freely about it, the former meshing with the wide-faced gear and the latter with the reversing gear 79. The gears 81 and 82 are provided with clutch teeth and a clutch 83 splined to the shaft 80 may be moved into contact with either of them to cause the shaft 80 to be rotated in one direction or the other or to be held inoperative by leaving the clutch in its central idle position.

Passing now to the mechanism by which the knee is elevated either by power or manually; the knee drive shaft 80, which is journaled in the removable front plate 66 at 95 and also in the knee structure at 96, carries a bevel gear 97 meshing with a larger bevel gear 98 on a vertical axis. As is shown in Fig. 3, the gear 98 has a shank 99 mounted in anti-friction bearings 100 carried

by the knee, the gear being held to these bearings by a shoulder on one side and by a threaded collar 101 on the other. The shank 99 is held by screws 102 to the enlarged top 103 of the elevating screw 104 which extends downwardly toward the base. The elevating screw passes through a nut 105 held as by threading in the upper end of a tube 106. This tube slides through a bearing 107 in the bottom of the knee, the bearing being preferably provided with a stuffing box 108 to prevent entrance of dirt or leakage of oil. The tube is clamped at 109 against rotation in the base A.

For manual operation of the knee elevating mechanism a shaft 110 is provided, extending parallel to shaft 80 through the front plate and bearing a handle 111. As appears in Fig. 1 this shaft has fixed on it a gear 114 which meshes with a gear 115 on shaft 80. By turning handle 111 shaft 80 is rotated independently of the driving gears 81 and 82 and the knee elevating mechanism adjusted.

I claim:

A knee structure for milling machines and the like comprising a frame, a hollow knee vertically movable on the frame, a vertical splined shaft journaled for rotation upon the frame and having a free end extending upwardly into the knee, a gear splined to the shaft, distributing gearing within the knee coupled to said gear, and a tubular member having a closed upper end and secured to said gear in position to completely enclose that part of the splined shaft above the gear and within the hollow knee to form an oil seal, said closed upper end being remote from the gear a distance substantially corresponding to the maximum vertical travel of the knee.

FRANK W. CURTIS.
